UNITED STATES PATENT OFFICE.

JOHN C. LINCOLN, OF CLEVELAND, OHIO, ASSIGNOR TO THE LINCOLN ELECTRIC COMPANY, OF CLEVELAND, OHIO, A CORPORATION OF OHIO.

METHOD OF AND MEANS FOR TRANSFORMING DIRECT CURRENT.

1,227,809.

Specification of Letters Patent. Patented May 29, 1917.

Application filed February 2, 1912. Serial No. 674,892.

To all whom it may concern:

Be it known that I, JOHN C. LINCOLN, a citizen of the United States, resident of Cleveland, county of Cuyahoga, and State of Ohio, have invented a new and useful Improvement in Methods of and Means for Transforming Direct Current, of which the following is a specification, the principle of the invention being herein explained and 10 the best mode in which I have contemplated applying that principle, so as to distinguish it from other inventions.

My invention relates to methods of and means for transforming direct current, its 15 object being to effect such transformation with a minimum loss of power. A specific object of the invention is to utilize such transformation in connection with the use of the electric arc for welding, electric arc- 20 lighting and other similar purposes.

To this end, my invention consists of a method and means hereinafter fully described and particularly set forth in the claims.

25 The annexed drawings and the following description set forth in detail one mode of carrying out my invention, the described mode, however, constituting but one of various forms in which the principle of the 30 invention may be applied.

In said annexed drawings:

Figure 1 illustrates diagrammatically a transformer embodying my invention and connected with an arc-circuit.

35 Fig. 2 is a diagram showing connections with a transformer embodying my invention and arranged to manually control the current at the arc.

Fig. 3 is a simplified diagram of the arrangement shown in Fig. 2.

The embodiment of my invention in so far as relates to the means for transforming direct current, comprises a central rotary armature A, a field structure B, and a circuit 45 J arranged so that the current therein may be applied for the purpose of welding or repairing castings.

This field structure is provided with four poles, each of which is divided into two parts, a part C of lesser cross-section, and a part C' of greater cross-section. The pole- 50 portions C' of greater cross-sections have two field-windings upon them, a winding D

of comparatively high resistance, and a winding E of comparatively low resistance. 55 The pole-portions C of smaller cross-section have wound upon them windings D' of resistance similar to that of the windings D, in series with the latter and connected with the main brushes F and F'. These windings 60 D and D' are therefore connected in shunt in the apparatus.

The windings E of low resistance are in series with each other, a secondary brush G and an exterior arc-circuit J. This secondary brush is located so as to be intersected by a plane passing through the axis of the armature A and midway between the two pole portions C and C'.

For the purpose of illustration, I will assume that the supply current in the main lines H H is of 220 volts, and that it is required that a maximum voltage of 110 be obtained at the arc. To obtain this result, I make the cross-sectional area of the pole- 70 portions C one-half that of the pole-portions C' and provide one-half the number of ampere turns of winding D on the pole portions C' as are provided upon the pole-portions C. 75

The difference of potential at the brushes F and F' would therefore be 220 volts, and the current passing through the shunt field will remain constant under all conditions. The connections are furthermore such, as 80 will be observed, that the difference of potential between the brushes G and F' is substantially equal to the difference of potential between the terminals in the arc-circuit J,—i. e., between the movable terminal or carbon K' and the casting K. It therefore follows that any change in the difference of potential between these two brushes is accompanied by a similar change in the difference of potential between said two terminals. 85

Let it first be assumed that current is being supplied to the transformer but that the terminals K and K' are separated so that no arc is being formed. Under these conditions the current is flowing through 90 the shunt-windings D and D' only. A divided magnetic field is thus created between each complete pole and the armature, which field consists of two parts,—one between pole-portions C and the armature, and one 95 between pole-portions C' and the armature. 100

105

The number of ampere turns on each pole-portion C' being made half that on each pole-portion C , under the assumed conditions, the flux per square inch from pole-portions C is twice that per square inch from pole-portions C' , but the total flux from the one pole-portion is equal to the total flux from the other. The difference of potential between brushes F' and G being proportional to the flux from the small pole-portion C , the voltage at the arc terminals is therefore 110, the amperage being zero.

Let it now be assumed that the main line is supplying a current of 220 volts to the field and armature, and that the terminals K and K' are in contact, the arc-circuit being therefore short-circuited. A current will, hence flow from the brush F through the armature windings subtended by the brushes F and G , through the arc-circuit, and through the series windings E . The introduction of the brush G , however, will also provide a circuit for a generated current which will be set up by the armature windings subtended by the brushes F' and G . This circuit includes also the series-winding E and arc circuit J which are of low resistance. When the brushes F' and G are short-circuited through the series winding and terminals K , K' , there will be a heavy generated current and a large motor current which will combine to produce an armature pole at the point G in the armature. The connections are such that this pole is of the same sign as that produced by the shunt windings D and D' on the poles C' and C . When this armature pole is strong enough, there will be no net flux from the pole C . The series winding on the pole C' is provided for the purpose of strengthening this pole as the generated current increases. By this means the flux is transformed from the pole C to the pole C' with an increase in the current in the arc circuit.

Also as before, the magneto-motive force due to the shunt windings D exists, and the resultant flux is, in the illustrated device and as previously stated, substantially one-half per square inch of area of that flowing from the pole portions C . The series windings E , however, are in the same direction as the shunt windings D , and are of a nature such that the current passing therethrough sets up an additional flux substantially equal to that which would flow from pole-portions C under conditions of no current in the arc-circuit. The difference of potential therefore, between the brushes F and G becomes 220 and the total flux gained in the magnetic zone between the pole-portions C' and the armature is substantially equal in amount to the flux lost in the magnetic zone between the pole-portions C and the armature. The total flux, therefore,

from one complete pole to the armature remains constant and the speed of revolution therefore remains constant, inasmuch as the flux multiplied by speed is always a constant quantity.

As a matter of fact, however, in practice, I prefer to arrange the windings in a manner such that the increase in flux due to the current flowing through the series-windings will be greater than the decrease in flux from pole-portions C , so that the armature will slow up when the terminals are caused to short-circuit the circuit J , for the purposes of safety, by avoiding any possibility of the motor "running away."

Let it now be assumed that the movable terminal or carbon K' is withdrawn from the casting and an arc formed. The effect of this withdrawal is to increase the resistance between the two arc terminals, and consequently to decrease the amount of current flowing through the arc-circuit, which means that the amount of current flowing through the series-windings is also decreased. The result of this is that first, the counter-magneto-motive force due to the arc current is reduced and the magneto-motive force establishing the flux from the pole-portions C to the armature overbalances this counter-magneto-motive force, so that the net result is a positive flow of magnetic lines from pole-portions C . The flux, however, from the pole-portions C' to the armature is correspondingly reduced and this magnetic field weakened and substantially in the same proportion as the field between the pole-portions C and the armature is strengthened. The voltage between the brushes F' and G , becomes of a quantity expressed by a figure less than 110, and which I will assume by way of illustration is 50 volts.

Let it now be assumed that the working conditions are such that the movable terminal or carbon K' is still further removed from the casting and the resistance is still further increased in consequence thereof. The result of this will be to still further strengthen the magnetic field between the pole-portions C and the armature, and correspondingly weaken the magnetic field between the pole-portions C' and the armature, thus increasing the difference of potential between the brushes F' and G , and correspondingly increasing the difference of potential between the terminals in the arc circuit. An increased resistance at the arc, therefore, is accompanied by an increased voltage and which is the desired end to be attained. This resistance may, therefore, be increased until the two portions of the divided magnetic field become of equal strength and the difference of potential between the brushes F' and G becomes 110, i. e., equal to the difference of potential be-

tween the brushes F' and G, which is the maximum voltage which may be obtained at the arc without having the latter blow out.

The above described device is suitable for 5 use in connection with successive operations of welding or repairing which present substantially constantly recurring like conditions, as for instance where the successive pieces to be welded are of constant or substantially constant size and material.

It is desirable upon the one hand to maintain the arc as short as possible in order to keep the voltage as low as possible in order to reduce the consumption of power. On 15 the other hand it is desirable to keep the arc as long as possible in order to prevent the material of the negative electrode from being transferred to the material to be operated upon, as in the case of a carbon negative electrode operating in connection with steel castings. Such castings are usually required to be as free as possible from hardness, and when the arc is too short, such carbon is transferred to the casting and under the influence of the attending heat produces a high-carbon or hard steel, which is to be avoided.

A normal voltage should therefore be selected which will combine the above required conditions to the greatest and the undesirable conditions to the least degree. Experience has shown that 50 volts will produce the best compromise between the above two conflicting sets of requirements, and I 35 have therefore adopted that as the normal voltage at the arc.

The said embodiment of my invention illustrated in Fig. 1 is arranged so that the relation of amperage to voltage will be represented by a single curve determined by coordinates representing voltage and amperage. The character of the work to be performed however, may be of such a varying nature that it is sometimes desirable to 45 change the amperage at the arc and impart to said curve a more or less rapidly drooping characteristic, or in other words cause the difference in flux from the small pole-portions and the large pole-portions to 50 change with greater or less rapidity, relatively to the amperage at the arc, so that the normal voltage obtained at the arc may be coincident with a greater or less amperage in the arc circuit.

55 Fig. 2 shows, by way of illustration, the connections and arrangement whereby I get a normal voltage of 50, and an amperage of one-quarter, one-half, three-quarters and the full maximum of 400 amperes in the arc-circuit. It will be readily understood by those skilled in the art, however, that the connections may be so varied or amplified that any desired proportion of the maximum current may be obtained having the assumed normal voltage of 50.

In order to obtain this desired result, I arrange the connections and field windings as they are diagrammatically illustrated in said Fig. 2. In the arrangement both pole-portions are provided with the shunt-windings D and D', and the larger pole-portions with the series-windings E, the functions of which are precisely those of the analogous elements in the apparatus illustrated in Fig. 1. In addition, however, I provide an additional winding E' on each small pole-portion and connect them with the series-windings E as hereinafter described. An external resistance R is introduced in the circuit together with the switches #1, #2 and #3. 70 These switches are provided and arranged so that their manipulation will give the fractions of or the whole of the maximum current desired, in this instance 100, 200, 300 and 400 amperes, as will hereinafter appear. 75 The single-throw single-pole switch #1 makes and breaks connection with the two terminals f and f'; the single-throw double-pole switch 2 makes and breaks connection with the terminals g g and g' g'. The double-throw double-pole switch #3 may 80 connect terminals h h with terminals h' h' or h² h². 85

When the lowest amperage at the arc, 100 amperes in this instance, or what I shall designate as "adjustment number 1," is desired, switches 1 and 2 are opened so as to break the corresponding circuits and switch 3 is thrown into its first or down position as shown in full lines in Fig. 2.

100 In this position of the switches the series-windings E and E' are all in series with each other as may be readily seen by an inspection of Fig. 3. The connections and relationship of the parts may be exactly determined from an inspection of Fig. 2 which is a complete wiring diagram. Referring to this figure, the current comes from the main line, passes through the starting box L, and passes into the line l, from which it flows 105 into the main brush F. From the latter it, together with the current generated in the armature winding, passes through the armature into brush G, through connection l', into connection l², and into the upper two of 110 the four series-windings E E, through the medium of connection l². From the latter through connection l⁴, it reaches one of the terminals h, whence it passes, through switch 115 #3 into one of terminals h², through connection l⁵, the series-coils E' E' E' E' successively, and connection l⁶, to the other terminal h², through switch #3, to the remaining two coils E E, through the medium of connection l⁷. From the left-hand lower coil E, it then passes through connection l⁸ to the arc-circuit J. From the latter it reaches terminal l⁹ of switch L' where the motor-portion of the arc current passes into the other main line H, the generated-portion 120

125

130

thereof passing through connection l^{10} to the other main brush F' , and thence through the armature to brush G , thus completing the circuit. The direction of the current 5 through the series-windings E' is such that, when the connections are as just described, it will set up a magneto-motive force counter to that set up by the shunt-windings D' , so that these small pole-portions may be described as "differentially wound." The effect of such counter or opposing action will be to reduce the net flux from the small portions C to the armature while current is flowing and an arc is being formed, and a 10 current of approximately $1/4$ the maximum will produce the required weakening of the flux from the small portion, and therefore the voltage between brushes F' and G will be the normal or approximately 50 volts.

15 By now throwing switch #3 in the other or "up" position as shown in dotted lines in Figs. 2 and 3, "adjustment number 2" is obtained in which the windings E' are entirely cut out and the four windings E connected two each in series and the two sets in parallel. In this case, the current takes the path described in connection with "adjustment number 1" until it reaches the terminal h , in which course it has passed through the two 20 upper coils E E . Instead of passing through connections l^5 , however, which before made the series connection with the coils E' E' E' E' , it passes directly into the arc-circuit through the medium of terminal 25 h' and connection l^{11} . The switch being in the described position, the current also passes from connection l^2 , to the other terminal h , connection l^7 and so through the two lower coils E E in series through connection l^8 30 into the arc-circuit as before. All opposing action of the windings E' is hence eliminated and the magnetic reactions are similar to those described in connection with Fig. 1. As compared with the result obtained in "adjustment number 1," the action of the series-windings D becomes one-half as strong for 35 a given current since the coils E are now connected in series parallel. A corresponding increase of current at the arc is effected 40 for said given or normal voltage, so that the normal voltage being still 50 but the amperage being 200, the volt-ampere curve is less markedly drooped in character than in the case of "adjustment number 1."

45 By now leaving switch #3 up and closing switch 1, the resistance R is introduced in parallel with the series-windings E , which are left in series-parallel, windings E' being still cut out.

50 The connections are now precisely those described with relation to adjustment number 2, excepting that current now passes from right-hand terminal h' through connection l^{12} through said resistance R and so 55 into the arc-circuit. This resistance is of a

character such that it will take the same current as each of the two sets of coils E E ,—that is the resistance is of substantially the same amount as that of each of the two pairs of coils E E now in parallel therewith. 70 A further weakening in the effect of the series-windings E is thus produced with a consequent still further less droop in the characteristic curve. The relation between the ampere turns in the armature and the ampere 75 turns in the series and shunt fields, are approximately the same in the third adjustment (when the resistance R is in parallel) with the fields E which are in series-parallel as the corresponding relation which has already 80 been described in connection with the device illustrated in Fig. 1.

Switch #2 being now closed, the conditions remain as just described excepting that the series-coils E' are re-introduced into the 85 circuit but the direction of the current flowing therethrough is reversed. Instead of an opposing action therefore, these windings E' augment the magneto-motive force created by the shunt-windings and consequently we 90 have a still further increase in current for the normal voltage at the arc, or 400 amperes, the maximum current.

Having fully described my invention, what I claim and desire to secure by Letters 95 Patent is:

1. In a direct current transformer, the combination of a field provided with symmetrically divided poles; an armature; main brushes; an intermediate brush; the windings on said armature being divided into two portions by the intermediate brush; part of the windings under one pole portion carrying a generated current; the pole portion opposite that part of the armature 100 winding carrying the generated current being provided with a shunt winding and the other portion being provided with a shunt winding and a series winding, the series winding being in the circuit carrying the 105 generated current, and so connected as to strengthen the corresponding pole portions 110 as the generated current increases.

2. In a dynamo-electric machine, the combination of a divided-pole field-structure; 115 an armature rotatably mounted in the field; an exterior circuit; means for shifting the flux from one pole-portion to another pole-portion; and additional means for producing a given shifting of such flux with currents of various amperage supplied to said exterior circuit.

3. In a dynamo-electric machine, the combination of a divided-pole field-structure; 125 each pole-portion provided with a shunt-winding and an additional winding; an armature rotatably mounted in the field; and switching mechanism whereby the additional windings on the part of pole-portions may be cut out of the circuit, and the addi- 130

tional windings of the other pole-portions may be connected in series-parallel in said circuit.

4. In a dynamo-electric machine, the combination of a divided-pole field-structure; each pole-portion provided with a shunt-winding and an additional winding; an armature rotatably mounted in the field; an exterior circuit connected with said armature; a resistance; and switching mechanism whereby the additional windings on part of the pole-portions may be cut out of the circuit, the additional windings of the other pole-portions may be connected in series-parallel, and the said resistance also connected in parallel with said series-parallel windings in the circuit. 15
5. In a dynamo-electric machine, the combination of a divided-pole field-structure; each pole-portion provided with a shunt-winding and an additional winding; an armature rotatably mounted in said field; means for connecting the additional windings on the one set of pole-pieces so that they augment the magnetic action of the shunt-windings on such pole-pieces; and means for adjustably connecting the additional windings of the other set of pole-pieces so as to augment or diminish the magnetic action of the shunt-coils on the same pole-pieces, according to the adjustment made. 20
6. In a dynamo-electric machine, the combination of a field-structure having poles each of which includes two divisional pole- 25
- 30
- 35
- pieces, one of which is of larger cross-sectional area than the other, each such pole-piece being provided with a shunt-winding and an additional winding; an armature rotatable in said field; means for connecting the additional windings on the pole-pieces of larger area so that they augment the magnetic action of the shunt-winding thereon; and means for adjustably connecting the additional windings on the pole-piece of lesser area so that they augment or diminish the magnetic action of the shunt-windings thereon, according to the adjustment. 40
7. In a dynamo-electric machine, the combination of a divided-pole field-structure, each of which includes two divisional pole-pieces, one of which is of larger sectional area than the other, each pole-piece being provided with a shunt-winding and a series winding; an armature rotatable in said field; means for connecting the series windings on the pole-pieces of larger area so that they augment the magnetic action of the shunt-windings on such pole-pieces; and means for adjustably connecting the series windings on the pole-piece of lesser area so as to augment or diminish the magnetic action of the shunt-windings on such pole-pieces, according to the adjustment. 45

Signed by me, this 29th day of January, 1912. 50

JOHN C. LINCOLN.
